UNITED STATES PATENT OFFICE

VERNON T. HOUGHTON, OF BRONXVILLE, NEW YORK, ASSIGNOR TO LEKTOPHONE CORPORATION, OF JERSEY CITY, NEW JERSEY, A CORPORATION OF DELAWARE

DESIGN FOR AN ACOUSTIC DIAPHRAGM

Application filed June 27, 1931. Serial No. 40,345. Term of patent 14 years.

To all whom it may concern:

Be it known that I, VERNON T. HOUGHTON, residing at Bronxville, in the State of New York, a citizen of the United States, have invention a new, original, and ornamental Design for Acoustic Diaphragm, of which the following is a specification, reference being had to the accompanying drawings, forming part hereof:

In the drawings Fig. 1 is a perspective

view of the acoustic diaphragm, and Fig. 2 is a mid-sectional view.

Having thus described and illustrated my invention, I claim:

The ornamental design for an acoustic diaphragm, substantially as shown.

In testimony whereof I have signed the foregoing specification.

VERNON T. HOUGHTON.
